UNITED STATES PATENT OFFICE.

HERBERT R. POLLEYS, OF NEW HAVEN, CONNECTICUT, ASSIGNOR TO NATIONAL INDIA RUBBER COMPANY, OF BRISTOL, RHODE ISLAND, A CORPORATION OF RHODE ISLAND.

CEMENTING MACHINE.

Application filed April 11, 1925. Serial No. 22,292.

To all whom it may concern:

Be it known that I, HERBERT R. POLLEYS, a citizen of the United States, residing at New Haven, county of New Haven, State 5 of Connecticut, have invented certain new and useful Improvements in a Cementing Machine, of which the following is a full, clear, and exact description.

This invention relates to a cementing machine, more particularly to a machine for cementing the lower portions and tip of a lasted shoe upper.

In the manufacture of rubber or composite fabric and rubber footwear, it is customary 15 in some styles of such footwear to apply a rubber strip known as a foxing to the lower portion of a lasted upper, which foxing generally extends between the sole and the upper in the finished article and not only 20 strengthens the article at this point but in the case of articles with fabric uppers it also waterproofs this portion of the article and it also strengthens the bond between the edge of the outsole and the shoe upper. In certain 25 types of footwear such as above mentioned, a rubber toe tip is also applied. In order to secure a better union between the upper and such foxing or toe tip, it is customary to cement those portions of the upper 30 to which the parts are applied, and in the case of footwear having fabric uppers, such cementing is in fact essential, since a good bond cannot be obtained directly between the fabric upper and the sheet rubber foxing 35 or toe tip applied to it. In addition to cementing around the upper at the point where the foxing is to be applied, it is desirable to have a thickened narrow portion or bead of cement at the edge of the cemented portion 40 at the point where the edge of the foxing is disposed. This bead of cement is desirable because of the fact that the edge of the foxing sometimes tends to curl away from the shoe, while the thickened bead of cement insures the adhesion of the foxing strip at this point. It is also necessary to cement the bottom of the lasted shoe.

Prior to my invention, the work of cementing the upper at the points where the foxing and toe tip are applied and the bottom or sole portion has been practically all 50 manually accomplished. To do this work manually requires a skilled and careful

operative in order that the cement may be evenly spread and the aforesaid thickened bead of cement formed at the edge of the cemented portion and that such edge may be even and not wavy. If through carelessness or inexperience the cemented portions are applied with an uneven or wavy edge, portions of cement extending beyond the foxing strip or toe tip mar the appearance of the finished article and may cause it to be classed as a second. Moreover the cost of such work when manually done is high, and the effort on the part of the operative to work rapidly increases the percentage of defective work. Comparatively few operatives possess the steadiness of hand and other physical qualifications necessary to do good work even 55 after long training.

An object of my invention is to improve the quality and reduce the cost of rubber and other footwear. Another object is to provide a rapid, accurate and economical 60 means for mechanically cementing desired parts of rubber or canvas and rubber footwear. Another object is to provide a machine for both cementing a portion of the article and forming a cement bead at the 65 edge of the cemented portion.

For a detailed disclosure of the nature and objects of the invention, reference is had to the accompanying specification and drawing, in which latter:

Figure 1 is a top plan view of the machine of my invention with parts removed for clearness;

Figure 2 is a side elevation of the machine;

Figure 3 is a detailed front elevation of the cement bead forming means with parts broken away;

Figure 4 is an enlarged and partly broken away detail of a cementing brush and cement bead applying device;

Figure 5 is an enlarged sectional view of the cement bead applying device;

Figure 6 is an enlarged detail of the toe tip cementing mechanism;

Figure 7 is an enlarged detail showing the manner of forming the cement bead; and

Figure 8 is a perspective of one of the toe tip cementing brushes.

Referring to the drawings, the numeral 105 1 designates the frame of the machine, at

the top of which is disposed a table 2 which is inclined at an angle of about 30° . A shaft 3 is journaled in bearings 4 and 5 at the back of the frame adjacent the top of the table, which shaft carries at one end a sprocket 6 driven by a chain 7 from any suitable source of power. A worm 8 is secured at the opposite end of the shaft 3, which worm drives a gear 9 mounted on a shaft 10, which latter carries adjacent its upper end a spur gear 11 meshing with another spur gear 12 mounted on the shaft 13. The shaft 13 extends up through a boss 14 within a cement receptacle 15 (Figures 2 and 5), and mounted on the upper end of the shaft is a cement distributing disc 16. This disc is formed at its lower side with a depending hub or flange 17 spaced somewhat from the upper end of the boss 14, and on the upper side of the disc 16 is a slightly elevated central circular portion 18. Oil is supplied to the shaft 13 by means of an oiler 19, and due to the extended engagement of the disc 16 against the upper end of the boss 14 and also to the spacing of the flange 17 from the boss there is no tendency for cement to get into the bearing of the shaft.

A housing plate 20 is removably secured to the upper portion of the receptacle 15 over the distributing disc 16, but it will be seen, more particularly in Figure 1, that this plate does not entirely cover the disc 16 but is cut away as shown at 21 to expose the lower portion of the disc, the cut-away edge 21 being substantially tangential to the raised circular portion 18 on the disc. A nipple 22 is formed in the housing plate 20, and a valved supply pipe 23 leading from a tank 24 is adapted to telescopically or otherwise engage the nipple to supply cement to the upper surface of the disc 16 within the housing 20. One purpose of the disc 16 is to supply a thickened bead of cement from its edge to a footwear article, and in order that cement may pass out on the exposed portion of the disc only at its edge, the following construction is provided: Adjustably secured by set screw and slot connection to the housing plate 20 at its cut-away edge 21 is a scraper 25, and by reference to Figure 3 it will be seen that this scraper at its right hand end is cut away at the point 26 in any desired manner, for instance at an angle of about 45° , while similarly adjustably secured to the housing plate 20 through scraper 25 adjacent the cut-away portion is an auxiliary scraper 27 which does not entirely cover the cut away portion of the scraper 25, thereby forming with the scraper 25 and disc 16 a small substantially triangular opening 28 directly at the edge of the disc through which opening cement may escape as the disc 16 rotates. By adjusting the scrapers 25 and 27, the

position of this opening may be varied to enlarge or reduce the size of the cement bead at the edge of the disc 16. Any surplus cement supplied to the disc 16 which does not escape through the opening 28 flows off the disc and down past the cut-away corner of plate 28^a to the incline 28^b (Figure 4) where it supplies a rotatable cementing brush to be described.

At an intermediate point on the shaft 10, a spiral gear 29 is mounted, which gear engages a spiral gear 30 secured on shaft 31, and the latter through the bevel gears 32 and 33 drives a shaft 34 which in turn through bevel gears 35 and 36 drives a shaft 37. The shaft 37 extends upwardly through a boss 38 on the receptacle 15 and carries at its upper end the rotary cement brush 39. In order to prevent cement from getting into the bearing of shaft 37, a cap 40 fits closely against the upper end of boss 38 (Figure 4) but is spaced from the sides thereof, and a shoulder 41 on the shaft 37 bears closely against the cap 40. An inclined shoe support or table 42 is adjustably secured by thumb nut 42^a to the table 2 in front of the brush 39, and it will be noted from Figure 2 that the brush is inclined with respect to the table 42 and projects above the latter to a height sufficient to form the desired coat of cement at the bottom of the shoe upper when the latter is resting on the table 42 and pressed against the brush. The vertical distance between disc 16 and table 42 governs the height to which cement is applied, and by adjusting table 42 this distance may be varied.

Leading from the bottom of the receptacle 15 is a cement drain pipe 43 emptying into a tank 44, and the tanks 44 and 24 are preferably interchangeable, so that when the tank 24 is empty one may be substituted for the other.

The above described mechanism is used for cementing around the lower portion of the shoe upper at the point where the foxing strip is to be supplied, and in cases where it is also desired to apply a toe tip, means are furnished for cementing the toe of the upper as follows: One or more brushes 45 are removably held adjacent the left hand side of the distributing disc 16 (Figs. 1, 3 and 6) by the flanges 46, and these brushes are supplied with the surplus cement from the disc 16. Below the brushes is mounted a small table 47, which table is carried on a rod 48 adjustably secured by the set screw 49.

In operation the machine is started and cement is supplied to the rotating disc 16 from the tank 24. Due to the scrapers 25 and 27 the cement supplied to the disc can only escape from beneath housing 20 through the opening 28 at the edge of the disc, so that in this manner a bead of ce-

ment is formed on the exposed edge of the disc as it passes out from the housing 20. The surplus cement as before stated drains down through the receptacle 15 to the incline 28^b where more or less of it is picked up by the rotating cementing brush 39. The operator then holds the footwear article 50 which is to be cemented on the table 42 in about the position shown in Fig. 10 4, pressing it upwardly so as to lightly engage the rotating brush 39 and rotating disc 16, at the same time turning the shoe gradually on its bottom. In this manner a coating of cement is applied along the lower 15 part of the upper by the brush 39, and at the same time the upper draws off the bead of cement from the edge of the disc 16, and due to the position of the disc the cement bead is applied at the upper edge of the 20 band of cement applied by the brush 39. Due to the inclination of the brush 39 a portion of the shoe bottom is also cemented, and as some of the cement from brush 39 flows on the table 42 this is picked up by the shoe 25 bottom as the shoe is rotated by the operator. The cement on the shoe bottom may if desired be then more uniformly distributed as by passing it across a brush or in any other desired manner. When a toe tip is 30 also to be applied the operator then places the footwear article 50, toe downwardly, on the table 47 with the sole portion directed outwardly and the toe of the upper pressed against the brushes 45 about as in Fig. 6, and 35 he then rotates the shoe or other article about its toe while pressing it against the brushes, thereby applying a coat of cement at the point where the toe tip is to be secured and marking the toe cap line.

40 It will be seen that by the invention the cementing operation can be rapidly and accurately performed, and since the shoe rests solidly on its bottom during the cementing operation, as shown in Fig. 4, the 45 cement strip on which the foxing is to be applied will be both uniform in thickness and its upper edge will be uniformly straight and without the wavy mark frequently occurring when hand cementing is 50 used. At the same time a uniform bead of cement is applied at the upper edge of the foxing cement strip, insuring the proper adhesion of the foxing at all points and a neat finished shoe without any blotches of cement extending on the upper beyond the 55 foxing.

The machine is simple, easily operated, easily cleaned, and enables rapid work to be done by the operator, thereby lessening the cost of the cementing operation and insuring against any seconds through careless or inexperienced operators.

60 While a specific embodiment of the machine has been described, it is obvious that the disclosure will suggest numerous modi-

fications to those skilled in the art, and it is not desired to limit the invention otherwise than as set forth in the attached claims.

Having thus described my invention what I claim and desire to protect by Letters 70 Patent is:—

1. In a cementing machine, an inclined support for the sole portion of a footwear article, means extending above the support whereby a coat of cement may be applied 75 to the lower portion of the upper of the article as the latter is rotated on the support, and means for supplying cement to said last means.

2. In a cementing machine, an article support, means whereby a band of cement with a thickened edge or bead may be applied to an article on the support, and means for supplying cement to said last means. 80

3. In a cementing machine, an article support, means whereby a band of cement may be applied to an article on the support, and means whereby a thickened bead of cement may be applied to the edge of said band. 85

4. In a cementing machine, an article support, means whereby a band of cement may be applied to an article on the support, and means whereby a thickened bead of cement may be simultaneously applied to the edge 90 of said band.

5. In a cementing machine, an article support, rotary means whereby a band of cement may be applied to an article disposed on the support, and rotary means whereby a bead of cement may be applied to the edge 100 of said band.

6. In a cementing machine, an article support, a rotary cementing brush projecting above said support, a rotary disc adjacent the upper end of said brush, and means for 105 supplying cement to said brush and to the edge of said disc adjacent the brush.

7. In a cementing machine, an inclined article support, a rotary cement applying brush projecting above the support and inclined thereto, and means for applying a bead of cement at the edge of the portion of the article cemented by the brush. 110

8. In a cementing machine, an article support, article cementing means projecting above the support, a rotary disc adjacent said means, a housing partly covering said disc, means for supplying cement between the housing and disc, and means cooperating with the housing and disc to form a 120 cement discharge aperture adjacent the edge of the disc.

9. In a cementing machine, an article support, article cementing means projecting above the support, a rotary disc adjacent said means, a housing partly covering said disc, means for supplying cement between the housing and disc, means cooperating with the housing and disc to form a cement discharge aperture adjacent the edge of the 130

- disc, and means for conducting excess cement from said disc to said first cementing means.
10. In a cementing machine, an article support, a cement receptacle, a rotary brush projecting from said receptacle above the support, a rotary disc adjacent the receptacle and brush, means for supplying a cement bead to the edge of the disc adjacent the brush, and means in the receptacle for conducting excess cement to the brush.
11. In a cementing machine, a footwear article support, means whereby a cement coating may be applied to a portion of an article thereon, means whereby a bead of cement may be applied to the edge of said coating, a second support, and means adjacent said second support whereby an additional portion of the article may be cement coated.
12. In a cementing machine, a footwear article support, means whereby a cement coating may be applied to an article thereon, means whereby a cement bead may be applied to the edge of the coating, and means adjacent said last means and supplied with cement therefrom whereby an additional portion of the article may be cement coated.
13. In a cementing machine, a footwear article support, rotary means for supplying a band of cement to a portion of an article disposed on said support, rotary means for applying a bead of cement to the edge of said band, and means for varying the size of said bead.
14. In a cementing machine, a footwear article support, a rotary cement applying brush extending above the surface of said support, a rotary cement bead applying disc above said brush, a housing partly covering said disc, means disposed at the edge of said housing for directing a bead of cement to the edge of the disc, and means for supplying cement between the housing and disc.
15. In a cementing machine, an inclined footwear article support, an inclined rotary brush extending above the surface thereof, a rotary cement bead applying disc adjacent and above said brush, and means for supplying a bead of cement to the edge of said disc.
16. In a cementing machine, a footwear article support, means whereby a band of cement with a thickened bead may be applied to an article on the support, and means for varying the size of said bead.
17. In a cementing machine, a footwear article support, a rotary cement applying brush projecting above the surface thereof, a housing, a cement bead applying rotary disc partially disposed below said housing and having a projecting portion adjacent said brush, means for supplying cement between said housing and disc, and means for forming a bead of cement on the edge of the projecting portion of the disc.
18. In a cementing machine, a footwear article support, a rotary cement applying brush projecting above the surface thereof, a housing, a cement bead applying rotary disc partially disposed below said housing and having a projecting portion adjacent said brush, means for supplying cement between said housing and disc, a scraper disposed on the housing and extending adjacent the projecting portion of the disc, and a second scraper forming with the edge of the disc and the first scraper a cement outlet.
- Signed at New Haven, in the county of New Haven, and State of Connecticut, this 4th day of April 1925.

HERBERT R. POLLEYS.
